UNITED STATES PATENT OFFICE

SAMUEL C. CARNEY, OF TULSA, OKLAHOMA, ASSIGNOR TO SHELL PETROLEUM CORPORATION, A CORPORATION OF VIRGINIA

PROCESS FOR EVAPORATING REFRIGERANT LIQUIDS

Application filed November 26, 1926. Serial No. 150,760.

This invention relates to improvements in processes for evaporating a refrigerant liquid, and consists in the novel procedure hereinafter disclosed.

5 In the ordinary flooded system of evaporation of simple substances commonly used as refrigerating agents, the refrigerant boils at a fixed temperature and produces a fixed cooling effect upon the load. In addition to 10 the ordinary substances, such as ammonia, sulphur dioxide and carbondioxide and other refrigerating agents of uniform and fixed composition, it has been found that hydrocarbon liquids made up of fractions having 15 different boiling points are also desirable as refrigerating agents. The composite hydrocarbon liquids used as refrigerating liquids, however, essentially do not have a common boiling point, but a boiling range due to the 20 different boiling points of the fractions composing the refrigerating liquid.

The mixtures of hydrocarbon obtained as by-products from the stabilizers of known type for stabilizing the gasoline product and 25 which, upon condensation, are suitable for refrigerating agents, ordinarily would have a substantial boiling range, for instance, from 20 degrees to 75 degrees Fahrenheit between the initial and final boiling point of the mixture.

It is the purpose of the present process to provide a method of evaporating such refrigerating agents having a substantial boiling range, whereby, by proper control, the refrigerant may be evaporated at practically a constant temperature.

The process may be better understood by reference to the apparatus employed and diagrammatically illustrated in the drawing.

40 The refrigerant to be evaporated is supplied from any suitable source through a supply pipe 1 which connects into a header 2 having connection with evaporating units that are spaced apart and arranged parallel with each other. The evaporation units comprise

shells having a series of inclined tubes 3 that connect into heads 4 and 5. The lower heads 4 are in communication with the header 2, and the upper heads 5 are connected by pipes 6 into a tank 7, the pipes entering the tank 50 substantially intermediate its height. A pipe 8 leads from the bottom of the tank 7 and connects into the header 2. There is a cross connection from the pipe 1 to the bottom of the tank 7 controlled by a valve 9. 55

The supply of the refrigerant liquid is controlled by a liquid level valve mechanism 10 which mechanism can be adjusted so that the height of the refrigerant in the base of the tank 7 may be held at a predetermined level. 60

The material being cooled, which may be either gas, gas and liquid mixed, or liquid alone, is admitted to the shell of the evaporating units through a supply pipe 11 that has branches 12 and 13 communicating respectively with the shells of the evaporating units. The fluid material circulates about the tubes 3 and is discharged through branches 14 and 15 of a discharge pipe 16. 65

A thermostat 17 is located in the product 70 discharge line and is operatively connected with a vapor pressure regulating valve 18 located in the vapor line 19, leading from the head of the tank 7, or optionally the thermostat may be connected with a valve that controls the speed of a compressor (not shown) with which the vapor line is connected, the purpose being to maintain a regulated back pressure in the vapor line. 75

The principle of the operation of the apparatus described is that the refrigerant liquid is carried in the tubes 3 and also a residual supply thereof carried in the lower part of the tank 7, the upper part of the tank above the level of the liquid constituting a vapor chamber. The material to be cooled circulates downwardly over the tubes 3 which heats the tubes throughout their length, thereby causing the liquid within the tubes 3 to boil and the vapor which it gives off entrains boil- 80 85 90

ing liquid and causes liquid to flow at a high velocity upwardly through the tubes and circulate by thermo-siphon action downwardly through the tank 7 and by the pipe 8 and the header 2 to the lower end of the tubes.

As a consequence of this continuous flow of the refrigerant liquid mixed with the vapor, the surfaces of the tubes through which heat is transmitted from the load is continuously 10 coated with boiling liquid which is moving at high velocity as the vapor from this boiling liquid continuously leaves the inner surface of the tube and travels upwardly through the central part thereof out of contact with 15 its inner surface. There is thus discharged into the tank 7 through the pipes 6 mixed liquid and vapor which separate by gravity, the unevaporated liquid returning to the lower part of the tank 7 and the vapor accumu- 20 lating in the head of the tank.

I am, of course, aware of processes for evaporating a refrigerant liquid having a fixed boiling point according to the flooded system. The problem, however, of the evaporation of 25 a refrigerant in a flooded system having a boiling range is quite distinct from that of evaporating a refrigerant with a fixed boiling point as it involves a different principle.

A refrigerant comprising components having 30 different boiling points where part of the composite liquid remains in the liquid phase and part passes into the vapor phase, and the liquid and vapor components are in intimate contact at any given combination of tempera- 35 ture and pressure, the composition of the liquid and of the vapor in contact with it bear a definite relation to each other and the control factors of temperature and pressure do not act the same as they do in connection with a 40 simple liquid used as a refrigerant. As has heretofore been pointed out, simple refrigerants boil at a fixed temperature and their cooling effect is constant at a given pressure, whereas in refrigerants having boiling range, 45 the boiling points may be varied by pressure and by the amount of the composite mixture remaining in the liquid phase and that passing into the vapor phase. The residual liquid, therefore, has a direct effect upon 50 the cooling action of the vaporization that results from a part of the liquid passing into the vapor phase. In the case of a simple liquid the unevaporated portion has no effect on the temperature produced by the part thereof 55 that passes into the vapor phase.

Moreover, there is a distinct difference between a process of evaporating a refrigerant having a boiling range under conditions 60 where part of the refrigerant remains in the liquid phase, and a process under which the composite refrigerant is evaporated by the expansion principle. In evaporating a composite refrigerant on the expansion principle 65 there is no equality of temperature in the

refrigerating unit and there is no possibility of accurate control.

In the present process there is a decided practical advantage because of the increased rate of heat transfer secured, and the highly 70 accurate and simple form of temperature control. This will be apparent from the consideration of the operation of the process. In the operation of the present process, if it be assumed that the refrigerant made up of components having a boiling range is supplied in the pipe 1 and the entire refrigerating unit is empty, by manipulating a hand operated valve 20 the rate of evaporation can be controlled so that only a part of the refrigerant 75 liquid will be evaporated. By continuing the introduction of the refrigerant liquid a quantity of unevaporated liquid will accumulate until the liquid level thereof reaches a point for which the float mechanism 10 is set. 80 When this condition has been attained the material to be cooled is admitted to the shells of the evaporators and passed down exteriorly of the tubes 3 and toward the heads 4. The refrigerant liquid will thereupon begin 85 to boil and will reduce the residual liquid in the bottom of the tank 7. Upon the reduction of the liquid level the liquid control 10 operates to admit a further supply of the refrigerant liquid. When the temperature of 90 the material being cooled reaches a point for which the thermostat 17 is set, the thermostat will sufficiently close the pressure regulating valve 18 to maintain a predetermined pressure on the evaporating liquid. This adjustment will permit the evaporation only of a sufficient amount of liquid to maintain the 95 temperature of the circulating unevaporated refrigerant to bring about the desired cooling 100 action.

The portion of the liquid that passes into the vapor phase is evacuated from the tank 7 and is compressed and constantly returned to the system so that the make-up of the refrigerant is continued uniform.

The component of the original mixture that passes into the vapor phase does so at a higher temperature or a lower temperature in the presence of the heavier liquid than if it were evaporated out of the presence of the least volatile liquid. Therefore the component of the refrigerant remaining in the liquid phase directly effects the evaporating of the component that passes into the vapor phase.

The component of the liquid that remains in the liquid phase constitutes a body through which the cooling effect, produced by the evaporation, is distributed equally through the cooling surfaces in the heat exchanger and this temperature will be uniform throughout the entire refrigerating element.

Furthermore, the temperature produced by the evaporation of the liquid that passes into the vapor phase is accurately controlled by

the thermostat that regulates the back pressure, which thermostat is within the direct and immediate influence of the product discharged from the refrigerating unit. This is a matter of considerable importance because any desired temperature within the boiling range of the composite refrigerant can be produced.

It will be understood that the vapor from the vapor line 19 is recondensed and returned to the system in such a way as to constitute the refrigerant supply entering the system through the pipe 1, except for such additional fluid as may be required to maintain the necessary refrigerant supply.

The process, therefore, may be operated economically and with assurance of a constant temperature exchange with the load. It is obvious also that the principle of the invention may be practiced on apparatus of various types and it is to be understood, therefore, that the apparatus disclosed is merely in exemplification of an operative apparatus for the purpose of practicing the process of the invention.

What I claim and desire to secure by Letters Patent is:—

1. A process of refrigeration which consists in evaporating the lighter part of a liquid hydrocarbon refrigerant having components of different relative volatility while maintaining the other part of the refrigerant in the liquid phase; withdrawing the evaporated part; condensing said evaporated part; and reintroducing the condensed part into the residual body of the liquid refrigerant.

2. A process of refrigeration which consists in circulating a body of hydrocarbon refrigerant, including components having different boiling points, counter-current to the fluid to be cooled; evaporating thereby a lighter part of the refrigerant while maintaining the other part of the refrigerant in the liquid phase; withdrawing the evaporated part; condensing said evaporated part; and automatically controlling the reintroduction of the condensed part into the residual body of liquid refrigerant.

3. A process of refrigeration which consists in evaporating the lighter portion of a liquid refrigerant, comprising a mixture of volatile hydrocarbons, in the presence of an excess amount of the liquid remaining in the liquid phase; removing the vapors; controlling the pressure on the liquid automatically in relation to the temperature of the cooled product; and continually supplying to the body of the liquid refrigerant a quantity of liquid hydrocarbon equal in weight and composition to the evaporated portion withdrawn.

4. A process of refrigeration which consists in evaporating the lighter portion of a liquid refrigerant mixture composed of fractions in solution, having different boiling

points, in the presence of an excess amount of the liquid remaining in the liquid phase; removing the vapors; controlling the pressure on the liquid automatically in relation to the temperature of the cooled product; and continually supplying to the body of liquid refrigerant a quantity of liquid equal in weight and composition to the evaporated portion withdrawn, thereby automatically controlling the composition and amount of the circulating body of refrigerant.
